UNITED STATES PATENT OFFICE.

VICTOR W. PAGÉ, OF NEW YORK, N. Y.

DESIGN FOR A VEHICLE STEP.

Application filed January 17, 1922. Serial No. 236. Term of patent 7 years.

To all whom it may concern:

Be it known that I, VICTOR W. PAGÉ, a citizen of the United States, and a resident of the city of New York, Kew Gardens, borough of Queens, in the county of Queens and State of New York, have invented a new, original, and ornamental Design for a Vehicle Step, of which the following is a specification, reference being had to the accompanying drawing, in which the figure is a perspective view of a vehicle step showing my new design.

I claim:

The ornamental design for a vehicle step, as shown.

VICTOR W. PAGÉ.
